(57) **CLAIM**

The ornamental design for a deflector for helmet visor, as shown and described.

DESCRIPTION

FIG. 1 is a front perspective view of a deflector for helmet visor showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view thereof taken in the direction of line 8-8 in FIG. 2; and,

FIG. 9 is another front perspective view thereof showing the deflector for helmet visor in a state of use in which it is attached to a helmet visor that is shown in broken lines to illustrate an example environment.

The evenly-dashed broken lines in the figures depict portions of the deflector for helmet visor, and the example helmet visor shown in FIG. 9, all of which form no part of the claimed design.

The dot-dash broken lines in the figures represent a boundary of the claimed design and form no part thereof.
